METAL LATH

Charles H. Scammell, Forest Hills, N. Y., assignor
to Charles H. Scammell Company, New York,
N. Y., a corporation of New York

Application January 16, 1935, Serial No. 1,993

5 Claims. (Cl. 72—116)

This invention relates particularly to metal lath of that type in which sheets of expanded or perforated metal or wire netting carry a backing sheet against which plaster or other plastic material 5 may be molded and the desired clench of the plaster secured with a comparatively small amount of plaster. The invention includes, also, constructions in which backing sheets are used on both sides of metallic lathing for shielding 10 or other purposes. Such metal lath in different forms forms the subject matter of my Patents Nos. 1,210,849, 1,499,408, and 1,569,144.

The object of the invention is to provide an improved metal lath in which the metallic lathing shall be provided on one or both sides with a transparent and water-proof sheet, so that no additional layer of water-proof material is required and the lathing may be quickly and conveniently positioned in use, the studs or other 20 members to which the lath is to be attached being visible through the transparent sheet or sheets, so that no marker on the lath is required.

Transparent and water-proof materials of different types may be used, but preferably a flexible, transparent, and water-proof sheet of cellulose material will be used, and I have found that the material known in the trade as "Cellophane" is well adapted for such use, this material having the above qualities, and in addition the 30 quality of not breaking up or cracking on driving nails or staples through the lath for securing it in position.

For a full understanding of the invention, a description of a construction embodying the invention in a preferred form, as applied in a lath for holding plaster, will now be given in connection with the accompanying drawing, and the invention then specifically pointed out in the claims.

40 In the drawing:

Figure 1 is a face view of a portion of the backed lath applied to studs or similar furring in a wall construction; and

Figure 2 is a section on the line 2 of Figure 1. Referring to the drawing, the studs 10 are secured in position in the usual way with respect to a joist 11, and the floor (not shown). The metal lath consists of the expanded metal or other open mesh metallic lathing 12, and the transparent and water-proof backing sheet 13, which are shown as secured to the studs by staples 1, although it will be understood that any other suitable securing means may be used. The lathing is covered with the body of plaster or concrete mixture 14, this being broken away to illustrate the lath construction. The backing sheet 13 is shown as secured to the metallic lathing by

adhesive 2, which may be asphalt composition, and conveniently applied by running the metallic lathing over a roller carrying the adhesive. Other means for securing the backing sheet to the lathing may be used. 5

As shown in the drawing, the studs are visible through the backing sheet, so that no marker is necessary, and the lath may readily and conveniently be secured in position simply by laying the sheets of lath over the studs and stapling the 10 lath to the studs, after which the plaster or other plastic material is applied.

If the invention be applied in connection with sheathing having backing sheets on both sides of the metallic member, the construction is the same 15 and may be secured in position in the same way by attaching means passing through both sheets of lath. In such sheathing lath, the metallic member will not be used to hold plastic composition, but the inner side of the sheathing may be 20 treated in any desired manner.

It will be understood that the lath may be used in connection with widely different building constructions and attached to either wood or metal supports, the transparency of the lath making it 25 excellently adapted for use in connection with metal work, on which attaching members are liable to be irregularly spaced, rendering it difficult to properly apply and position non-transparent lath. 30

What is claimed is:

1. A new article of manufacture comprising metallic lathing having secured thereto a backing of transparent and water-proof material.

2. A new article of manufacture comprising 35 metallic lathing formed to anchor plastic material between it and a plane surface in contact with such lathing, and a backing sheet of transparent and water-proof material secured to said lathing. 40

3. A new article of manufacture comprising metallic lathing formed to anchor plastic material between it and a plane surface in contact with such lathing, and a backing sheet of transparent and water-proof material secured to said 45 lathing by adhesive.

4. A new article of manufacture comprising metallic lathing having secured thereto a backing of transparent and water-proof cellulose material, such as "Cellophane". 50

5. A new article of manufacture comprising metallic lathing formed to anchor plastic material between it and a plane surface in contact with such lathing and a flexible, transparent and water-proof backing sheet of cellulose material, 55 such as "Cellophane", secured to said lathing.

CHARLES H. SCAMMELL.
